United States Patent Office.

E. H. BLOEBAUM AND C. H. NAGEL, OF ST. CHARLES, MISSOURI.

Letters Patent No. 82,375, dated September 22, 1868.

IMPROVED DINING-TABLE.

The Schedule referred to in these Letters Patent and making part of the same.

TO ALL WHOM IT MAY CONCERN:

Be it known that we, E. H. BLOEBAUM and C. H. NAGEL, of St. Charles, in the county of St. Charles, and State of Missouri, have made certain new and useful Improvements in Dining-Tables; and we do hereby declare that the following is a full and clear description thereof, reference being had to the accompanying drawings, and to the letters of reference marked thereon.

This invention relates to an improvement in dining-room tables, of a circular form, wherein an annular rim, of sufficient width to sustain the plates of the guests, is placed, so as to surround the centre field of the table, whereon the dishes containing the viands are placed.

The centre part of the table is made to revolve on its axis, so as to be turned around by the guests, in order to bring any particular dish near any person.

The general arrangement of the table-top is such that it may be folded up, so as to fit the corner of a room, when not in use.

To enable those skilled in the art to make and use our improved table, we will proceed to describe its construction and operation.

Figure 1 of the drawings is a top plan of the improved table as it appears when ready for use.

Figure 2 is a bottom plan of the same.

Figure 3 is a bottom plan of the central section, the surrounding annular rim being removed in this figure.

Figure 4 is a top plan, showing the top folded up into its position for fitting the corner of the room.

Figure 5 is a central sectional elevation.

The top of the table is composed of a central circular field, A, and a surrounding annular rim, B. Each of these parts of the top is composed of four pieces, viz, the central one, of the pieces $a^1 a^2 a^3$, and the outer or rim-piece, of the separate pieces $b^1 b^2 b^3$. The piece a has one square corner and two straight sides, the remaining side being a segmental curve, drawn from the centre of the table. This central piece a is large enough of itself to form a respectably-sized table, suitable for the corner of a room, and it is supported on the pivot c , which rests on the turn-table C, and also on the conical rollers c' . This construction permits the central field A to be turned around on its pivot c , when all the parts are in the positions to form a complete table, as is shown in figs. 1, 2, and 5. The whole table-top thus constructed rests on a frame, D, and legs $d^1 d^2 d^3 d^4 d^5 d^6$. The portions of the frame D intermediate between the legs $d^1 d^2 d^3$ are fixed in a stationary position, while the portions to which the remaining legs are attached are arranged to be folded up against this stationary framework, as shown in fig. 2, by the full-line drawings, or distended, so as to support the annular rim, as is shown by the dotted lines in the same figure.

The periphery of the central top A is rebated, for the reception of the inner edge of the rim B, which it overlaps, and sheaves, a^4 , in this rebating, receive the weight of the periphery of the part A, and diminish friction between it and the annular rim, when the inner part is turned around. The central part is also provided with knobs, a^5 , near its periphery, for the purpose of turning it around. The central piece A a is secured to the piece a^1 by the hinges a^6 , and to the piece a^2 by the hinges a^7 , while the piece a^3 is hinged to the piece a^1 by the hinges a^8 . Of the annular rim-pieces, those marked $b^1 b^2$ are hinged together by the hinges b^4 , while the button b^5 secures the remaining joint. Buttons a^9 and a^{10} , shown most clearly in fig. 3, strengthen and sustain the outer wings of the central board, when the parts are distended.

When it is desirable that the annular rim shall remain in a fixed relative position with reference to the central field, the hooks b^6 may engage the two parts, as is clearly shown in fig. 2.

The table constructed as above described, when used for a dining-table, the annular rim B will sustain the plates used by the individual guests, while the central board A will receive the dishes containing the unbroken food of the meal.

Each guest may, at pleasure, turn the central board, by seizing one of the knobs a^5 and whirling it around, so as to bring any of the dishes thereon in close proximity.

When not desired as a dining-table, all parts of the top but the pieces a and b may be folded down by the side of the legs, as in fig. 4, while the legs will be contracted, as shown by full lines in fig. 2.

Having described our invention, what we claim, is—

1. The central board A, when composed of the pieces a a^1 a^2 a^3 , and the annular rim B, when composed of the pieces b b^1 b^2 b^3 , when the said parts are united and arranged, substantially as herein shown and described, and for the purpose set forth.

2. The arrangement of the frame D and legs d d^1 d^2 d^3 d^4 d^5 d^6 , herein shown and described.

In testimony of which invention, we hereunto set our hands, in presence of—

E. H. BLOEBAUM,
C. H. NAGEL.
